UNITED STATES PATENT OFFICE.

HARRY T. ANDERSON AND ANDREW CHRISTIANSON, OF BUTLER, PENNSYLVANIA,
ASSIGNORS TO STANDARD STEEL CAR COMPANY, OF PITTSBURGH, PENNSYLVANIA, A CORPORATION OF PENNSYLVANIA.

CAR FOR HOT METAL.

Application filed May 20, 1924. Serial No. 714,854.

To all whom it may concern:

Be it known that we, HARRY T. ANDERSON and ANDREW CHRISTIANSON, citizens of the United States, and residents of Butler, in the county of Butler and State of Pennsylvania, have invented a new and useful Improvement in Cars for Hot Metal; and we do hereby declare the following to be a full, clear, and exact description thereof:

Our invention relates to cars for hot metal, and particularly to steel cars into which hot billets, ashes and other hot materials may be loaded without injury to the car.

In loading hot materials into ordinary steel cars the heat is sometimes so great and is retained for such length of time that the enameling or paint on the outside of the car blisters and peels off, destroying the lettering and removing the protective coating of the car.

The object of our invention is to not only protect the car against damage from the heat of material loaded thereinto, but to provide a reinforcing and protective means for the sides of the car. This is of particular merit when it is borne in mind when loading material, such as iron billets, that they are sometimes thrown against the sides of the car with excessive force, and furthermore, when magnets are employed for handling billets and the like, the magnet itself may swing against the sides of the car with great force.

Some of the forms which our invention may take are shown in the accompanying drawing wherein Fig. 1 is a transverse sectional view, in elevation, of substantially one-half of a car embodying our invention; Fig. 2 is a view, looking from the left of Fig. 1, with the side plates of the car removed; Fig. 3 is an enlarged detail view of a portion of the device of Fig. 1; Fig. 4 is a sectional view taken on the line 4-4 of Fig. 1, with the bottom sheets omitted, and Fig. 5 is a view similar to that of Fig. 3 but showing a modified form of structure.

The car is provided with a bolster 6, center sill 7, bottom sheets 8 and side sheets 9 of somewhat the usual construction. The side sheets 9 are supported from the bolster 6 by means of Z-bars 10, each having one of its flanges secured to the side sheets 9 as shown in Fig. 4, and the other flange secured to a supplementary side plate 11, the

lower portions of the bars 10 being provided with a web 12 that is riveted to the bolster 6. The upper ends of the side plates 9 are riveted to the depending flange of a top rail or cover plate 13, which adds stiffness to the structure and protects the upper edges of the side plates 9 and auxiliary plates 11 from damage. The auxiliary plates 11, at their upper ends, are secured by rivets 14 to the top rail 13; these rivets 14 also passing through angle members 15, which, at their lower ends, are riveted to the inside plate 11. The angle members 15 serve as an additional support for the top rail 13.

The Z-bars 10 serve not only as supports for the inside plates 11, but also function as ordinary car stakes to brace the sides of the car.

Referring to Fig. 5, the top rail 13 as a distinct element is dispensed with and the side sheet 9^a is provided with a horizontally disposed flange 13^a at its upper end. Furthermore the inside sheet 11^a corresponding to the side plate 11 of Fig. 1 is of slightly different form and the stiffening members 15 of Fig. 1 are dispensed with. In order to permit the attachment of the sheet 11^a to the side sheet 9^a, perforations 16 are provided in the side sheet 9^a at points opposite to where the rivets 14^a are to be placed. These openings permit the insertion of a tool for supporting the inner end of the rivet when it is being upset, as well as a means for ventilating the space between the sheets 9 and 11, as will hereinafter appear.

By reference to Figs. 1 and 2, it will be seen that the bottom sheets 8 extend only to a point below the auxiliary sheets 11, leaving the space between the sheets 11 and 9 clear, except for the bars 10 that are distributed at intervals along the sides of the car. This open space permits air to circulate, and thereby serves as an additional means by which the outside sheets 9 are protected from the heat. If desired, openings may also be provided at the upper ends of the spaces between the sheets 9 and 11, in a manner similar to that shown in Fig. 5, thus permitting air to circulate more freely between the sheets 9 and 11.

From the foregoing description it will be seen that the outside sheet 9 is protected against damage by iron bars thrown into the car and also from the effects of heat from

the hot iron billets, ashes and the like, in addition to which additional strengthening means are provided for the car.

It will be apparent that various changes in detail and general arrangement may be made without departing from the spirit and scope of the invention as defined in the accompanying claims.

We claim as our invention:

- 10 1. The combination with a car provided with a side sheet, of an auxiliary inside sheet, means for mounting said inside sheet in spaced relation to said side sheet, and a top rail disposed above one of said sheets and mounted in fixed relation thereto.
- 15 2. The combination with a car provided with a side sheet, of a spacer member connected thereto and projecting inwardly, and an inside sheet disposed against the inner surface of said spacer member, the said inside sheet being inclined upwardly from the bottom of the car.
- 20 3. The combination with a car provided with a bolster and a side sheet, of an inside stake member secured to said side sheet and

bolster respectively, and an inside sheet disposed against the inner surface of said stake member.

4. The combination with a car provided with a side sheet and a bolster, of a bar of Z-form at its upper portion and provided with a web at its lower portion, an inside sheet, means for securing one of the flanges of said Z-section to the side sheet, means for securing the other flange thereof to the inside sheet, and means for securing the web portion of said bar to the bolster.

5. The combination with a car provided with a side sheet, of an auxiliary side sheet mounted in spaced relation to said side sheet, and means for permitting circulation of air between said side and inside sheets.

6. The combination with an open-top steel car provided with a side wall, of an inside wall mounted in spaced relation thereto.

In testimony whereof we, the said HARRY T. ANDERSON, and ANDREW CHRISTIANSON have hereunto set our hands.

HARRY T. ANDERSON.

ANDREW CHRISTIANSON.
